HOISTING ANCHORAGE FOR CAR ROOFS

Original Filed July 30, 1928

UNITED STATES PATENT OFFICE

ALFRED R. WILSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE

HOISTING ANCHORAGE FOR CAR ROOFS

Application filed July 30, 1928, Serial No. 296,289. Renewed October 7, 1930.

This invention relates to railway freight cars and has particular reference to an improved roof structure for railway freight cars.

5 An object of this invention is to provide a car roof having means constituting a firm anchorage for the attachment of suitable hoisting mechanism for hoisting cargoes within the car. A further object of this invention is to provide a hoist anchorage for a railway car which will not reduce in any way the loading capacity of the car which, as generally figured, must be clear to the interior height of the sides of the car body.

10 15 A still further object of the invention is to provide a hoist anchorage which may be attached to the ridge pole of the car roof and which may likewise be attached to the carlines of the car roof.

20 25 A still further object of the invention is to provide a hoist anchorage which may be spaced from the car roof so that a chain or the like may be passed over the anchorage and which will further be provided with means for supporting a hoist loop or the like.

30 35 Other objects and advantages of this invention will become more apparent as the following description proceeds, particularly when reference is had to the accompanying drawing wherein like reference characters designate corresponding parts throughout all views and wherein

Figure 1 is a cross section through a railway car showing a hoist anchorage constructed in accordance with the teachings of this invention installed on the same.

40 Figure 2 is a fragmentary longitudinal sectional view through the car shown in Figure 1 and

45 Figure 3 is an enlarged sectional view taken substantially on the line 3-3 of Figure 2.

50 Referring now particularly to the drawing, there is fragmentarily illustrated a car roof having a ridge pole A and the carlines B. The carlines B are preferably of the type having end portions B' parallel with the sloping roof and a central portion B² which passes horizontally beneath the ridge pole A. The ends of the sloping portions B'

of the carlines may be supported on the side plates C in accordance with the usual practice.

The present invention contemplates in particular the provision of an anchorage beam or lifting rail which may be firmly secured to the roof structure and which will not obstruct the loading capacity of the car. Accordingly there is provided a beam D which extends longitudinally of the car roof and below the ridge pole A. The beam D is preferably in the form of a channel member having its web at the top and provided on its opposite sides and at the bottom thereof with outstanding flanges D' for a purpose hereinafter to be more fully described.

55 60 65 As clearly illustrated in Figure 2 of the drawing the beam D is preferably spaced from the ridge pole A for the greater portion of its length to provide a clearance between the ridge pole A and the beam D through which a rope, chain or other anchorage or hoisting means may be passed. To provide this clearance the beam D is formed at spaced points with the upwardly offset portions D² 70 75 adapted to engage the under side of the ridge pole A and to pass between the ridge pole A and the carlines B. For attaching the beam D to the ridge pole A suitable bolts E may be passed through the ridge pole A and through the web of the offset portion D² of the beam D as clearly illustrated in Figures 2 and 3 of the drawing. It is also preferable to secure the beam D to the carlines B and accordingly the flanges D' of the offset portion D² of the beam D are riveted or otherwise secured to the carlines B as at F.

80 85 90 95 As brought out before, the beam D is provided with the outstanding flanges D' at the bottom of its sides and if desired there may be provided a suitable hoisting loop G having the inturned end portions G' adapted to hook over the flanges D'. The loop G is of sufficient strength to carry the load to be hoisted and by virtue of its support on the flanges D' may be shifted longitudinally of the car to substantially any positions desired.

95 100 From the above it is believed that the structure and mounting of the hoisting rail will be readily apparent. The rail extends longi-

- tudinally of the car roof below the ridge pole A being spaced from the ridge pole for the major portion of its length whereby suitable hoisting ropes or chains may be passed between the lifting rail D and the ridge pole A. The lifting rail D is provided with the flanges D' adapted to support a hoisting loop G, which loop may be moved longitudinally of the car between the carlines B. Further 10 the lifting rail D is provided with the offset portions D² which pass between the carlines B and the ridge pole A, these offset portions being secured both to the ridge pole A and the carlines B thus producing a firm mounting 15 for the beam D. It will be obvious that any load supplied at any point to the beam D will be distributed not only to the ridge pole A but also to the carlines B. Further, by virtue of the fact that the offset portions D² of the 20 lifting rail pass over the carlines B, the load on the lifting rail D will be transmitted to the body of the carlines B rather than to the attaching means between the lifting rail D and the carlines B.
- 25 One mechanical embodiment of the inventive idea has been described with considerable detail but it is to be clearly understood that the description is for the purpose of illustration only. The right is therefore reserved to make such changes in the details of construction and arrangement of parts as will fall within the purview of the attached claims.
- What I claim as my invention is:
- 30 1. The combination with a car roof having a ridge pole, of a beam engaging and secured to said ridge pole at a plurality of spaced points, said beam constituting a hoist anchorage.
- 35 2. The combination with a car roof having a ridge pole, of a beam having an offset portion secured to said ridge pole, said beam constituting a hoist anchorage.
- 40 3. The combination with a car roof having a ridge pole, of a beam constituting a hoist anchorage arranged adjacent said ridge pole, said beam having a portion spaced from said ridge pole and a second portion engaging said ridge pole and secured thereto.
- 45 4. The combination with a car roof having a ridge pole, of a beam extending longitudinally of said roof beneath said ridge pole, said beam being secured to said ridge pole and in contact therewith and constituting a hoist anchorage.
- 50 5. The combination with a car roof having a ridge pole, of a beam extending longitudinally of said roof beneath said ridge pole, said beam having a plurality of spaced offset portions secured to said ridge pole.
- 55 6. The combination with a car roof having a ridge pole and a carline, of an anchorage beam having a portion arranged between said ridge pole and carline.
- 60 7. The combination with a car roof having

a ridge pole and a carline of a beam arranged between and secured to said ridge pole and carline, said beam constituting a hoist anchorage.

8. The combination with a car roof having a ridge pole and a carline, of a beam having an offset portion arranged between said ridge pole and carline and secured thereto, said beam constituting a hoist anchorage. 70

9. The combination with a car roof having a ridge pole and a plurality of carlines extending transversely thereof, of a beam extending longitudinally of said roof below said ridge pole and above said carlines, said beam constituting a hoist anchorage. 75

10. The combination with a car roof having a ridge pole and a plurality of carlines extending transversely thereof, of a beam extending longitudinally of said roof, said beam being spaced from said ridge pole for the major portion of its length and having offset portions extending between said ridge pole and carlines and secured thereto. 85

11. The combination with a car roof having a ridge pole and a plurality of carlines extending transversely thereof, of a beam extending longitudinally of said car roof, said beam being of inverted channel shape and having outstanding flanges at the bottom of its sides, means securing the base of said beam to said ridge pole at spaced points and means securing the flanges of said beam to said carlines. 90

12. The combination with a car roof having a ridge pole and a plurality of carlines extending transversely thereof, of a beam extending longitudinally of said roof below said ridge pole, said beam being spaced from said ridge pole for a major portion of its length and having offset portions engaging said ridge pole and carlines and secured thereto, and flanges formed on said beam for slidably supporting a hoisting loop. 100

13. The combination with a car roof having a ridge pole, of a beam constituting a hoist anchorage supported adjacent said ridge pole, said beam having a portion spaced from said ridge pole and a second portion engaging said ridge pole. 110

14. The combination with a car roof having a ridge pole, of a beam constituting a hoist anchorage supported adjacent said ridge pole, said beam being provided with a plurality of spaced offset portions engaging said ridge pole whereby the major portion of said beam is maintained in spaced relation to said ridge pole. 115

In testimony whereof I affix my signature.
ALFRED R. WILSON.
